MICROCHEMIST'S SYRINGE

Clark H. Hamilton, Oakland, Calif.

Application December 21, 1949, Serial No. 134,240

5 Claims. (Cl. 73—425.6)

1

My invention relates to means useful in connection with the work of a microchemist to assist him in measuring relatively minute quantities of materials in an accurate and reproduceable way.

In microchemistry and particularly in handling radio active materials, it is necessary to provide a means for measuring small volumes of material. The volumes are of the order of one lambda in magnitude, one lambda being a millionth of a liter. It is often necessary for the microchemist to manipulate his equipment inside of a hood provided with rubber gloves, so that he is not irradiated. Manipulation of equipment by use of gloves and within a hood is difficult at best and in operating a micromeasure to obtain accuracy under these conditions is a severe chore.

It is therefore an object of my invention to provide a microchemist's syringe effective for accurate operation by the chemist even while gloved or operating in a gloved hood.

A further object of the invention is to provide a microchemist's syringe effective to meter quantities of material accurately and reproduceably.

Another object of the invention is to provide a microchemist's syringe readily operable with one hand.

Another object of the invention is to provide a microchemist's syringe simple to manufacture, to clean, and to handle.

Another object of the invention is to provide a microchemist's syringe of a relatively inexpensive construction.

A still further object of the invention is to provide a microchemist's syringe which is in general an improvement over syringes now available.

Other objects together with the foregoing are attained in the forms of my invention described in the accompanying description and illustrated in the drawings in which

Figure 1 is a cross section on a longitudinal axial plane through one form of microchemist's syringe in accordance with my invention.

Figure 2 is a cross section on a longitudinal axial plane through a modified form of microchemist's syringe of my invention.

While variations in the particular form of my invention can be made depending upon the environment in which it is to be principally utilized and depending somewhat upon the preferences and facilities of an individual user, it has successfully been embodied in the forms illustrated herein. In the arrangement shown particularly in Figure 1, I provide a generally tubular body 6 of glass or other comparable, inert ma-

2

terial formed throughout most of its length with a smooth, circular-cylindrical bore 7. At its lower end, the body is diminished in cross section to provide an external taper 8 adapted to interfit with any standard pipette; for example, a one lambda pipette, and to provide an internal passage 9 merging with the interior bore 7. At its other end, the body 6 is provided with a reinforcing lip 11 or flange affording a convenient point for grasping by the user and affording an abutment for his thumb or fingers.

Disposed within the bore 7 is a circular-cylindrical sleeve 12 preferably formed of stainless steel or comparable inert material and circular-cylindrical in cross section to provide a smooth exterior surface 13. The surface 13 very carefully fits the bore 7 so that the sleeve 12 is slideable within the body 6 and is also rotatable in the body.

The interior of the sleeve 12, especially adjacent its inner or lower end is formed with threads 14 of the customary helical kind. A similar group of threads 16 at the lower end of a plunger 17 engages these threads. By this threaded engagement, the plunger 17 is rotatable and axially movable within and with respect to the sleeve 12. A stem 18 extends from the plunger 17 through the sleeve 12 and emerges from one end thereof in an extension 19. A suitable bushing 21 or bearing is disposed between the sleeve 12 and the stem 18 as an additional support and guide. On its extended end 19 the stem 18 carries a thumb wheel 22 held in place by a set screw 23 so that thumb wheel and the stem 19 as well as the plunger 17 rotate in unison.

It is a characteristic of my microchemist's syringe that the friction of turning the plunger 17 within the sleeve 12 to produce axial translation or motion of the plunger is less than the rotational resistance between the sleeve 12 and the interior of the body 6. This is accomplished in any of several ways, partly by carefully coordinating the relative fit between the sleeve 12 and the bore 7 and the fit between the plunger threads 16 and the internal threads 14 in the sleeve 12. The friction is also a function of the lubrication, if any, between these relatively moving surfaces and I particularly provide that the lubricant, if used, between the sleeve 12 and the body 6 is somewhat heavier or more resistant to rotation than the lubricant between the plunger 17 and the sleeve 12.

In the use of the structure a pipette is attached to the extension 8. The microchemist then

grasps the body 6 with his little and ring fingers and utilizing his thumb and forefinger against the wheel 22 and in part resting upon the rim 11, withdraws the sleeve 12 axially from the body 6 in a small amount to induce some air to flow into the pipette. After immersing the pipette, he then withdraws the sleeve 12 farther utilizing a similar finger and thumb movement until material drawn into the pipette is nearly at a graduation mark. He then stops the axial movement of the thumb wheel 22 and rotates it. The resistance to turning between the sleeve 12 and the body 6 is sufficiently greater than the resistance to turning between the plunger 17 and the sleeve 12 that the plunger rotates. The plunger is withdrawn a very slight distance farther while the sleeve 12 remains in position due to the greater friction between the sleeve and the body 6 not only against rotational turning but also against any further axial withdrawal. In this way even though he is working with rubber gloves and at a distance in a hood the microchemist can accurately meter the contents of the pipette. The contents of the pipette, after coming exactly to the graduation, are expelled by simple axial depression of the thumb wheel 22.

In a comparable fashion the microchemist's syringe of Figure 2 is constructed to have a body 36 with a circular-cylindrical, smooth, interior bore 37 merging with a passage 38 for connection to or communication with a pipette. The body 36 at its upper end has an enlarged flange 39. Within the body a sleeve 40 is disposed. The external surface 41 of the sleeve fits within the bore 37 of the body 36 with a predetermined amount of friction against rotation and axial translation. The upper end of the sleeve 40 is provided with an enlarged finger member 43 carrying a bushing 44 within which a stem 46 is freely mounted. A thumb wheel 47 at the upper end of the stem is secured in place by a set screw 48 and imparts the movement of the thumb wheel to the stem. The lower end of the stem carries a threaded portion 51 engaging internal threads 52 on a plunger plug 53 located within and secured to the sleeve 40, preferably by cement. The relative friction between the threads on the plug 53 and the stem 46 and between the sleeve 40 and the body 36 is such that rotation of the thumb wheel 47 produces rotation of the stem and of the threaded portion 51 but produces only an axial translation of the plug 53 and the sleeve 40 within the body. The rotation of the wheel 47 does not produce any rotation of the plug 53 and the sleeve 40 within the body 36. The general operation of this form of structure is identical with that shown in Figure 1.

In both of these modifications, there is provided a microchemist's syringe very simply made and very simply cared for, fabricated of inexpensive materials and of inexpensive design. It is effective, for use in microchemistry even when the microchemist is encumbered by gloves and by the necessity of working within a hood. It

provides, in conjunction with standard pipette equipment, a means for measuring accurately and reproducibly minute quantities of chemical materials.

5 I claim:

1. A microchemist's syringe comprising a body having a smooth circular-cylindrical bore merging with an outlet passage, a circular-cylindrical externally smooth sleeve slidably disposed within said bore, said sleeve having internal threads, a plunger having threads engaging said internal threads, a stem on said plunger having one end extending beyond said sleeve, and a thumb wheel on the said end of the plunger.

10 15 2. A microchemist's syringe comprising a tubular body having a smooth circular bore, an externally smooth circular sleeve slidably disposed within said bore, said sleeve having internal threads, a plunger having threads engaging said internal threads, and means for turning said plunger with respect to said sleeve.

20 25 3. A microchemist's syringe comprising a tubular body having a smooth circular bore, an externally smooth circular sleeve slidably disposed within said bore and having a predetermined amount of frictional resistance to turning therein, said sleeve having internal threads, a plunger having threads engaging said internal threads and having a frictional resistance to turning 30 therein less than said predetermined amount, and means for turning said plunger with respect to said sleeve.

35 40 4. A microchemist's syringe comprising a body having a smooth circular bore, an externally smooth circular sleeve disposed within said bore in sliding engagement with said body, said sleeve having internal threads, and a plunger having threads engaging said internal threads, said plunger turning in said sleeve easier than said sleeve turns in said body.

45 50 5. A microchemist's syringe comprising a body having a circular-cylindrical smooth bore merging with an outlet passage, a circular-cylindrical externally smooth sleeve disposed within said bore in sliding engagement with said body, said sleeve having internal threads, a plunger having threads engaging said internal threads, said plunger turning in said sleeve easier than said sleeve turns in said body, a stem on said plunger having one end extending beyond said sleeve, and a thumb wheel on said end of the plunger.
